CONTROL SYSTEM

Slavo J. Murcek, Duquesne, Pa., assignor to Westinghouse Electric Corporation, East Pittsburgh, Pa., a corporation of Pennsylvania

Application March 3, 1945, Serial No. 580,762

5 Claims. (Cl. 177—352)

1

My invention relates to circuits for electric signalling and, in particular, relates to an arrangement for causing a preliminary signal to connect an incoming communication line to an outgoing communication line at an intermediate station.

It is frequently desirable to be able to use existing wire telephone or radio communication systems for the control of remotely positioned apparatus. For example, it may be desirable to cause the calling signal in a dial or other telephone exchange to connect the incoming line which the signal selects to an outgoing line leading to a public-address amplifier or the like.

One object of my invention is to cause the bell-ringer voltage in a telephone-communication system to connect the incoming line to an outgoing line leading to a work device.

Another object of my invention is to cause the bell-ringer voltage of a communication system to control the output current of a thyratron.

Still another object of my invention is to cause the signal voltage on a communication system to maintain a relay in closed position, as long as the signal persists.

Still another object of my invention is to provide an electronic relay system in which there is no substantial dissipation of power during standby periods.

Still another object is to provide an arrangement by which the controlling device in a system in which an incoming signal line is transferred to an outgoing line presents a constant impedance, when viewed from the controlled line.

Other objects of my invention will become apparent upon reading the following description, when taken in connection with the drawing, in which the single figure is a diagrammatic illustration of a circuit embodying the principles of my invention.

Referring in detail to the drawing, incoming lines 1, 2 are provided over which both bell-ringing or other control currents may be employed to interconnect incoming lines 1, 2 to outgoing lines 3, 4 over which signals or the like may be transmitted to a work device, such as a public-address amplifier. For example, ordinary bell-ringing signals coming in over the lines 1, 2 will cause the lines 1, 2 to be properly connected to the lines 3, 4, to transmit thereto telephone, voice, or other signals which may be broadcast from the public-address amplifier.

Shunted across the incoming lines 1, 2 is a condenser 5 in series with a pair of normally closed contacts 6 which are caused to open, when sufficient current flows through a relay winding

2

7. A relay winding 8 is connected in series with the contacts 6. In shunt with the contacts 6 and the relay winding 8 is the primary of an audio-frequency transformer 9, the secondary of which impresses its voltage upon the grid electrode of an electrical discharge tube 11. The tube 11 is preferably of the cold-cathode gaseous-discharge type, and its cathode is connected through a resistor 12 shunted by a condenser 13 to one terminal 14 of a source of alternating current which may be of commercial power frequency. The other terminal 15 of the source of alternating current is connected to the anode of the tube 11 through a resistor 16 which limits the initial current to capacitor 13 while permitting it to charge promptly. The terminal 15 is likewise connected through a pair of normally closed contacts 17 and the relay winding 7, already mentioned, to the anode of a second electrical discharge tube 18 which is preferably of the cold-cathode gaseous-discharge type. The control electrode and cathode of the tube 18 are shunted across the resistor 12.

The relay winding 7, when energized, opens a pair of normally closed contacts 19, 21 which are shunted by a resistor 22 and closes a pair of normally open contacts 23, 24. The line conductor 3 of the outgoing line is connected to the common junction of the contacts 19 and 23, and the line conductor 4 is connected to the common junction of the contacts 21, 24. The remaining contacts 23 and 24 are respectively connected to the two incoming line wires 1 and 2.

The mode of operation of the above-described circuit is as follows. The discharge tubes 11 and 18 are so related in design, to the voltage across the terminals 14, 15, that they remain non-conductive until positive impulses of voltage are impressed upon their respective control electrodes.

Under such circumstances, the relay winding 7 is deenergized and the contacts 6, 19, 21, 23 and 24 are in the position shown in the drawing. When the lines 1, 2 are substantially without energizing signals, the relay winding 8 is deenergized and the normally closed contacts 17 controlled thereby are closed.

When a ringing or other desired initiating signal appears on the lines 1, 2, sufficient current flows through the relay 8 to impress a positive voltage on the control electrode of tube 11, and thereby render it conductive. In order to insure that it is only the desired bell-ringing or other initiating signal which shall sufficiently energize the transformer 9, to render tube 11 conductive, the 50 capacitor 5, relay winding 8, and transformer

winding 9 may be tuned to resonate approximately at the frequency of the desired initiating signal. Current flow through the winding 8 will open the normally closed contacts 17 and thereby insure that the tube 18 can not receive voltage enough to energize it from the alternating-current lines 14, 15. This insures that the relay 7 will remain deenergized and the contacts 6, 19, 21, 23 and 24 remain in the position shown in the drawing until cessation of the ringing signal across the incoming lines 1, 2. However, current from the alternating-current lines 14, 15 flowing through the resistor 16 will be rectified by the discharge tube 11 and will gradually charge the condenser 13 to impress positive voltage on the control electrode of tube 18. As soon as the condenser 13 has charged to a sufficient positive voltage, the tube 18 will be put into a state where it is capable of conducting current as soon as the opened contacts 17 are closed, to reconnect it to the alternating-current lines 14, 15.

However, as previously stated, the contacts 17 will remain opened until the ringing signal on the lines 1, 2 ceases. Thereupon, closure of the contacts 17 will result in current flow from the alternating-current source 14, 15 through tube 18 and relay winding 7. Energization of the relay winding 7 will move the contacts 19, 21 to open position and the contacts 23, 24 to closed position, thereby connecting the incoming lines 1, 2 directly to the outgoing lines 3, 4; and will also open the contacts 6 to deenergize relay winding 8. Deenergization of relay 8 will prevent further waste of energy therein and likewise prevent it from attenuating the signal on lines 1 and 2 and disturbing the impedance match of those lines to outgoing lines 3, 4.

However, as long as signalling currents continue on the lines 1, 2, the transformer 9 will be energized sufficiently to maintain conductivity to current of tube 11 and thereby maintain the positive charge on the capacitor 13. This insures the maintenance of current flow through tube 18, thereby continuing relay winding 7 in its energized position and maintaining the contacts 23 and 24 in closed position, thereby connecting outgoing lines 3, 4 to incoming lines 1, 2.

Cessation of the signal on lines 1, 2 will cause the tube 11 to become non-conductive, thereby permitting the condenser to discharge through resistor 12. The value of resistor 12 is so proportioned to the condenser 13 that the latter does not become sufficiently discharged to drop the control electrode voltage in tube 18 enough to render that tube non-conductive until a time longer than any normal pause in the signal over lines 1 and 2. However, it is naturally contemplated that, when signals over lines 1 and 2 have ceased for a time longer than some predetermined period, this will indicate no further continuation of the immediate use of the public-address system or other work device connected to the lines 3, 4. The resistor 12 is accordingly so proportioned that it will discharge condenser 13 after the lapse of more than this predetermined period to so low a voltage that the tube 18 will become non-conductive. When this happens, relay 7 is deenergized, returning contacts 6, 19, 21, 23 and 24 to the condition shown in the drawing. The outgoing lines 3, 4 are thus disconnected from the incoming line 1, 2 and shunted by the impedance 22. The impedance 22 is made electrically equal to the impedance across lines 1 and 2 so that the outgoing lines 3, 4 have the same transmission characteristics as far as concerns other apparatus which may be connected

to it at points outside the limits of the present figure, whether contacts 23 and 24 are open or closed.

By reason of the fact that the tubes 11 and 18 are cold-cathode devices, utilizing no heated cathodes, and are deenergized at all times except when the lines 1, 2 have been energized to put the relay system into active condition, the dissipation of power in the above-mentioned system during standby or negative periods is negligible.

I claim as my invention:

1. In a transfer relay for responding to a control signal to connect an incoming line to an outgoing line, a condenser charged in response to energization of said incoming line, means for moving said relay from a first position to a second position in response to attainment of a predetermined charge by said condenser, means for maintaining said outgoing line disconnected from said incoming line when said relay is in said first position and for connecting said outgoing line to said incoming line when said relay is in said second position, and means for maintaining said relay in said second position as long as currents of a predetermined character are present on said incoming line.

2. In a transfer relay for connecting an outgoing line to an incoming line in response to initiating signals of a predetermined character, a first relay having an energizing winding connected in series with a first pair of separable contacts across said incoming line, a second relay having an energizing winding connected in series with a second pair of separable contacts which are opened in response to the energization of said first relay, and acting when energized to open said first separable contacts, an electrical discharge tube having a control electrode and having its principal electrodes connected in series with said second relay winding and said second separable contacts, a condenser shunted by a resistor connected to impress its voltage on said control electrode, means responsive to energization of said incoming line to charge said condenser, and means for causing energization of said second relay to connect said outgoing line to said incoming line.

3. In a transfer relay for connecting an outgoing line to an incoming line in response to initiating signals of a predetermined character, a first relay having an energizing winding connected in series with a first pair of separable contacts across said incoming line, a second relay having an energizing winding connected in series with a second pair of separable contacts which are opened in response to the energization of said first relay, and acting when energized to open said first separable contacts, an electrical discharge tube having a control electrode and having its principal electrodes connected in series with said second relay winding and said second separable contacts, a condenser shunted by a resistor connected to impress its voltage on said control electrode, a second electrical discharge tube having a control electrode connected to control current flow from a source for charging said condenser, means for impressing voltage from said incoming line on the control electrode circuit of said second electrical discharge tube, and means for causing energization of said second relay to connect said outgoing line to said incoming line.

4. In a transfer relay for connecting an outgoing line to an incoming line in response to initiating signals of a predetermined character, a

first relay having an energizing winding connected in series with a first pair of separable contacts across said incoming line, a second relay having an energizing winding connected in series with a second pair of separable contacts which are opened in response to the energization of said first relay, and acting when energized to open said first separable contacts, a cold-cathode electrical-discharge tube having a control electrode and having its principal electrodes connected in series with said second relay winding and said second separable contacts, a condenser shunted by a resistor connected to impress its voltage on said control electrode, means responsive to energization of said incoming line to charge said condenser, and means for causing energization of said second relay to connect said outgoing line to said incoming line.

5. In a transfer relay for connecting an outgoing line to an incoming line in response to initiating signals of a predetermined character, a first relay having an energizing winding connected in series with a first pair of separable contacts across said incoming line, a second relay having an energizing winding connected in series with a second pair of separable contacts which are opened in response to the energization of said first relay, and acting when energized to open said first separable contacts, a cold-cathode electrical-discharge tube having a control electrode

15

20

25

30

and having its principal electrodes connected in series with said second relay winding and said second separable contacts, a condenser shunted by a resistor connected to impress its voltage on said control electrode, a second cold-cathode electrical-discharge tube having a control electrode connected to control current flow from a source for charging said condenser, means for impressing voltage from said incoming line on the control electrode circuit of said second cold-cathode electrical-discharge tube, and means for causing energization of said second relay to connect said outgoing line to said incoming line.
